GARMENT HANGER TRACK

Carl Dahlberg, Duluth, Minn.

Application May 29, 1947, Serial No. 751,425

1 Claim. (Cl. 104—100)

1

This invention relates to a clothes hanger track and has special reference to improvements in switch joints for such track.

It is well known that in large cleaning establishments, laundries, and the like where many pieces of clothing are handled while suspended upon individual hangers and are frequently moved about in groups or batches, that much time and hard labor is wasted. During such moving and handling in groups by laborers upon their arm or shoulder accidents frequently occur by some of the garments falling or slipping to the floor or ground as the case may be, especially while being transferred from place to place for temporary storage and where trucks or drays having their own fixed hanger supports are employed necessitating individual carrying and shifting about of each hanger and its burden, the aggregate of damage is considerable.

To avoid much of this annoyance and unnecessary work as well as materially expedite the handling operations is the principal object of the instant invention.

Other objects, advantages, and expediences will appear as the explanation of the invention proceeds.

Referring now to the accompanying drawing forming part of this application:

Fig. 1 is an end elevation of a portable track utilizing my invention.

Fig. 2 is a plan view of a circuitous track made in accordance with the invention.

Fig. 3 is an enlarged broken vertical sectional view on the line 3—3, Fig. 2.

Fig. 4 is an enlarged side elevational view of the hinge corner connection at one end of the hanger receiving track.

Fig. 5 is a top plan view of Fig. 4.

Fig. 6 is a side elevational view of one of the switch connecting members.

Fig. 7 is a bottom plan view showing the said switch connecting member as installed.

Fig. 8 is a top plan view of Fig. 7.

This invention pertains to one specific utilization of the invention disclosed in my co-pending application Serial Number 692,268, filed August 22, 1946, and additional novel cooperative features for augmenting the use of same as applied to a portable rack.

As shown in the drawing, the track on which garments on hangers are moved is supported by means of goose-neck or angle brackets 9, the outer upwardly extending ends of each of which supports its respective portion of the garment hanger track 10. The support of the track 10

2

is accomplished by nipples 11 having suitable openings for ready vertical application of the end of the brackets 9 thereto, the complete disclosure of which is included in my aforementioned co-pending application.

At one end of the track is a hinge coupling member 12, shown in detail in Figs. 4 and 5, which is supported on one of the brackets 9 as by a suitably shaped opening 13 in the same manner as the nipples 11 are carried. One end of the hinge member 12 is screw-threaded or otherwise fixed to the track 10 so as to form a smooth uninterrupted surface in the track. As may be clearly seen in Figs. 4 and 5, the other end of the hinge member has a vertically disposed central tongue portion 14 which is adapted to pivotally carry the adjacent section of track 15 as by the pin 16 which extends therethrough. The track section 15 is bifurcated as at 17 to accomplish such connection and the ends thereof are rounded as at 18 to permit of vertical swinging of the track section 15, thus the same could be aptly termed a gate.

At the opposite end of the track section 15 is carried a switch connecting member 19, shown in detail in Figs. 3, 6, 7, and 8, having a vertically disposed central tongue member 20, which differs materially from the tongue 14 in that the bottom or lower portion thereof is cut-away as at 21, and also there is a small opening 22 axially of the tongue 20.

The cut-away portion 21 of the tongue makes for convenient insertion thereof vertically from above into the slot 8 in the upper half of the adjacent end of the cooperative pipe 23, which forms the housing of the latch attachment for the gate and also serves as a section of the track, the opposite end thereof being screwthreadedly attached to the adjacent nipple 11 supported on its bracket 9.

Within the housing 23 is installed a sliding bolt 24, biased towards the switch connection 19 by a helical spring 25 which abuts one end of the adjacent nipple 11. Screwthreadedly installed within the lower portion of the bolt is a depending operating finger 26, there being a suitable elongated slot 27 in the housing to permit of the sliding of the bolt by means of the finger 26. Extending outwardly from the center of the outer end of the bolt 24 is a dowel locking pin 28, which, when the bolt is in outermost position, locks the switch member 19 in closed position as by said dowel being held in the opening 22 in the switch 19.

It is deemed apparent that by using the con-

struction shown in the instant application, there will be a great saving in both time and labor, as the necessity of lifting garments from one track to another is eliminated.

Having thus described my invention, what I claim is:

A garment hanger track comprising a tubular member arranged circuitously with the ends thereof spaced from each other, a similar tubular member of a length to extend between said ends and be joined thereto to optionally form a continuous track, one end of said similar tubular member being pivotally joined to one end of said tubular member on an axis extending transversely of said tubular member, a connecting member forming the other end of said similar tubular member and constructed and arranged to form a cooperative connection with the other end of said tubular member, said connection comprising a housing forming a part of one end of said track, a bore longitudinally of said housing, a reciprocal bolt within said bore, means biasing said bolt towards the free end of said bore, means for manually moving said bolt against said biasing means, said housing having at its free end a vertical slot partially therethrough leaving a projecting ledge on the lower side thereof, said connecting member having a cut away lower portion which connects

with the cut out portion of said housing and is supported upon said projecting ledge, said connecting member being engageable by said bolt to lock said connection in united relation.
